UNITED STATES PATENT OFFICE.

CHARLES A. HUSSEY, OF NEW YORK, N. Y., ASSIGNOR TO THE HUSSEY ELECTRIC COMPANY, OF SAME PLACE.

ELECTRIC-ARC LAMP.

SPECIFICATION forming part of Letters Patent No. 267,691, dated November 21, 1882.

Application filed January 9, 1882. (No model.)

To all whom it may concern:

Be it known that I, CHARLES A. HUSSEY, of New York, in the county and State of New York, have invented certain new and useful 5 Improvements in Electric-Arc Lamps, of which the following is a specification.

My improvements consist in a voltaic-arc-electric lamp comprising two carbons or conductors, between which the arc is to be formed, means 10 for impelling them toward each other, means for connecting them so that one cannot be moved without occasioning motion in the other, and a stop against which one of the carbons or conductors bears, all being so combined and 15 organized that when the carbon or conductor which bears against the stop is arrested by the stop the other carbon or conductor is kept away sufficiently to form the voltaic arc. The stop may be of carbon or other conducting material, or of any suitable non-conducting material, and preferably will be adjustable, so as 20 to enable the carbons to come into contact to put out the light. When adjustable an electro-magnet may be employed in the lamp-circuit 25 to actuate it and render the lamp automatic. The carbons or conductors may be advantageously arranged at an angle to each other, and supported in rocking bearings. A spring or springs or the equivalent thereof will preferably 30 constitute the means for impelling the carbons or conductors toward each other. The means for connecting them so that motion in one will occasion motion in the other may consist of gear-wheels. When gear-wheels are 35 employed one is preferably made adjustable circumferentially on its shaft to provide for maintaining the carbons or conductors at different distances apart.

The improvements further consist in a novel 40 construction of an electric lamp, whereby the base-plate, carbons, their appurtenances, and also the globe may be detached conveniently.

In the accompanying drawings, Figure 1 is a perspective view of an electric lamp embodying my improvements. Fig. 2 is a view of the essential parts of the same on a larger scale. Fig. 3 is a plan of these parts on the same scale. Fig. 4 is a section of the lower portion of the cowl of the globe. Fig. 5 is a

view illustrative of the means whereby the 50 base-plate of the lamp is supported. Fig. 6 is a sectional view of these means. Fig. 7 is also a sectional view of these means. Fig. 8 is a detail view, illustrative of an adjustable gear-wheel, which is combined with the carbons. 55 Fig. 9 is a view illustrative of means which may be employed for separating the carbons to start the lamp. Fig. 10 is a sectional view of the same, taken in a plane at right angles to that of Fig. 9; and Fig. 11 is an inverted plan 60 of these means.

Similar letters of reference designate corresponding parts in all the figures.

A B designate two carbons, which are shown as of semi-cylindric shape, but may be of any 65 other suitable form. They are secured in sockets or holders A' B', which are mounted on rotary shafts A² B². The sockets or holders which I have shown consist each of two jaws, between which the lower end of a carbon fits, 70 and a set-screw passing through one of the jaws and impinging against the carbon, so as to clamp it against the other jaw. Applied to the shafts A² B² are springs A³ B³, which tend to rotate the shafts in such directions that they 75 will carry the upper ends of the carbons into proximity with each other. On corresponding ends of the shafts A² B² are pinions A⁴ B⁴, with which engage two gear wheels, C D, that also engage with each other. 80

It is obvious that each of the springs A³ B³, in acting to rotate the shaft to which it is applied, also serves, through the agency of these pinions and gear-wheels, to rotate the other shaft in the opposite direction, and consequently to impel the carbons toward each other. 85 For this reason I do not confine myself to the use of a separate spring for each of the shafts.

I will here remark that I do not desire to be restricted to the use of a spring or springs for 90 impelling the carbons toward each other, for I may find it advantageous to use a weight or weights or other equivalent devices.

The shafts A² B² and the shafts supporting the gear-wheels C D, are sustained in bearings 95 extending from metal-plates P P' P², which are connected to a base-plate, P⁴, of hard rubber or other insulating material.

Between the pinions A⁴ B⁴ and their shafts A² B² are placed bushings *a b* of hard rubber or other suitable insulating material, so that these pinions and the gear-wheels C D will 5 not make a short circuit in the lamp. The bushing *b*, which is applied to the shaft B², (see particularly Fig. 8,) has a flange or shoulder at the inner end, and the body or main portion does not extend as far forward as the pinion B⁴, which fits on it. In front of the pinion there is arranged on the shaft a washer, *b'*. A shoulder on a hand-screw, *c*, which is screwed into the end of the shaft, bears against this washer and serves to clamp the pinion B⁴ between it and the shoulder on the bushing, thereby 15 securing the pinion in position on the shaft. The bushing *b* is prevented from being forced backward on the shaft through the action of the screw by means of a shoulder on the shaft against which it bears. By loosening the screw the pinion may be adjusted on the shaft circumferentially, and by tightening the screw again the pinion will be retained in the position to which it is adjusted. The importance 20 of this feature will appear presently.

E designates a device against which and near its tip the tip of the carbon B rests. It serves as a stop for limiting the motion of the said carbon toward the carbon A. It is made 25 in the form of a narrow strip and occupies a vertical position, as here shown.

The pinions and gear-wheels are so combined with the shafts A² B² of the carbon-holders A' B' that when the tip of the carbon B comes 30 in contact with the stop the tip of the carbon A will be kept sufficiently away to form the voltaic arc. By adjusting the pinion B⁴ on its shaft the distance between the tips of the carbons may be varied to suit electric currents of 35 different electro-motive force.

The stop E may be made of kaolin or other suitable non-conducting material or it may be of carbon. When made of carbon it and the carbon B, which is in contact with it, will together 40 equal in bulk the bulk of the carbon A, providing the lamp is supplied with alternating currents of electricity. If, however, the lamp is supplied with a direct current, the carbon B and the carbon-stop E may form the positive 45 electrode, and then they will together have double the bulk of the carbon A, so that equal lengths of both the carbons A B will be consumed. As the carbons A B are consumed the stop E is correspondingly burned away. Hence 50 the carbon B is constantly impelled inward, and the carbon A has a corresponding movement, so as to preserve the relation between its tip and the tip of the carbon B. The rapidity of the feed or movement of the carbons 55 toward each other varies correspondingly to the consumption of the carbons.

The stop E is secured to a holder, E', consisting of two jaws, between which the stop fits, and a set-screw inserted in one of the jaws, 60 and adapted to impinge against the stop and secure it. The holder E' is provided with a

shank, E², which extends through a tube, P⁵, fitted in the base-plate, and is provided with a hand-piece, E³, of insulating material. A screw, *g*, inserted in this tube and entering a longitudinal groove in the said shank, serves to guide the stop, when adjusted, and also to clamp it in position. By loosening this screw the stop may be lowered to permit the carbons A B to come together and put out the light, 75 and by raising the stop and securing it in position by the said screw the carbons may be separated, and the voltaic arc established.

The circuit-wires G G' of the lamp extend down through a supporting-rod, H, to and thence through two arms or hangers, H', which depend therefrom. At the lower end they have attached to them metallic contact-pieces, I, which complete the circuit to the plates P P'. These contact-pieces are not fastened to the 85 said plates, but simply bear on them. The circuit is continued through these plates and thence to the shafts A² B², the carbon-holders A' B', and the carbons A B.

In Figs. 9, 10, and 11 I have shown an electro-magnet, J, introduced into the circuit for the purpose of operating the stop E. In this example of my invention the plate P is divided into two parts, which are insulated from each other by their attachment to the base-plate. 90 The electric circuit extends from that part of the plate P on which one of the contact-pieces I bears to the wire of this electro-magnet, and from the wire of the electro-magnet to the other part of the plate P, and thence the circuit is 95 continued, as before described. The armature of the electro-magnet is connected to a lever or levers, K, and the latter near their free ends are connected to a lever or levers, L, close to the fulcrum of the latter. The levers L are 100 connected with the shank of the holder in which the stop E is secured. When the electric current is supplied to the lamp the electro-magnet is energized, and, attracting its armature, raises the stop E into an operative position. When the electric current ceases the electro-magnet releases its armature, and the stop descends so as to permit the carbons A B to come together. I employ compound 105 levers, so that the armature of the electro-magnet can impart the requisite motion to the stop.

M designates a globe of glass or other suitably translucent or transparent material. To its lower end a metal ring, *h*, is secured by means of screws *i* lapping over a lip with which 110 the lower end is provided.

N designates hooks, which are hinged to the lower ends of the arms or hangers H', and are adapted to be engaged with the globe-ring *h*, so as to support it and the globe. By swinging the hooks inward the globe-ring will be released from them, and it and the globe may be passed downward over them and so removed. The base-plate P⁴, when in place, bears against the lower side of these hooks and precludes 115 their displacement. On the base-plate are lugs *j*, which are provided with screws *k*, that

5 by overlapping the globe-ring *h* secure the base-plate in place. As the contact-pieces *I* are not fastened to the plates *P P'* the base-plate and its appurtenances can be removed at any time by loosening the screws *k*, and it may be easily replaced when desirable.

O designates a cowl for the globe *M*. It may be made of sheet metal and of any desired form. As here shown it is adapted to

slide up and down on the rod *H*.

It will be seen that by my improvements I produce a very simple and desirable lamp.

What I claim as my invention, and desire to secure by Letters Patent, is—

5 1. In a voltaic-arc electric lamp, two carbons or conductors, between which the arc is to be formed, means for impelling them toward each other, means for connecting them so that one cannot be moved without occasioning motion in the other, and a stop against which one of the carbons or conductors bears, all being so combined and organized that when the carbon or conductor which bears against the stop is arrested by the stop the other carbon or conductor will be kept sufficiently away from it to form the voltaic arc, substantially as specified.

2. In a voltaic-arc electric lamp, two carbons or conductors, means for impelling them toward each other, means for connecting them so that one cannot be moved without occasioning motion in the other, and a stop of non-conducting material against which one of the carbons or conductors bears, all being so combined that when the carbon or conductor which bears against the stop is arrested by the stop the other carbon or conductor will be kept sufficiently away from it to form the voltaic arc, substantially as specified.

3. In a voltaic-arc electric lamp, two carbons or conductors, arranged at an angle to each other and adapted to rock or swing toward and from each other, means for impelling them toward each other, means for connecting them so that one cannot move without occasioning a motion in the other, and a stop against which one of the carbons or conductors bears, all being so combined and organized that when the carbon or conductor which bears against the stop is arrested by the stop the other carbon or conductor will be kept sufficiently away from it to form the voltaic arc, substantially as specified.

4. In a voltaic-arc electric lamp, two carbons or conductors, a spring or springs or the equivalent thereof for impelling them toward each other, means for connecting them so that one cannot be moved without occasioning motion in the other, and a stop against which one of the carbons or conductors bears, all being so combined and organized that when the carbon or conductor which bears against the stop is arrested by the stop the other carbon or conductor will be kept sufficiently away to form the voltaic arc, substantially as specified.

65 5. In a voltaic-arc electric lamp, two carbons or conductors, means for impelling them toward

each other, gear-wheels connecting them so that one cannot move without occasioning motion in the other, and a stop against which one of the carbons or conductors bears, all being so combined and organized that when the carbon or conductor which bears against the stop is arrested by the stop the other carbon or conductor will be kept sufficiently away to form the voltaic arc, substantially as specified.

6. In a voltaic-arc electric lamp, two carbons or conductors, a spring or springs or the equivalent thereof for impelling them toward each other, gear-wheels connecting them so that one cannot move without occasioning motion in the other, and a stop against which one of the carbons or conductors bears, all being so combined and organized that when the carbon or conductor which bears against the stop is arrested by the stop the other carbon or conductor will be kept sufficiently away from it to form the voltaic arc, substantially as specified.

7. In a voltaic-arc electric lamp, two carbons or conductors, means for impelling them toward each other, means for connecting them so that one cannot be moved without occasioning motion in the other, and an adjustable stop against which one of the carbons or conductors bears, all being so combined and organized that when the carbon or conductor which bears against the stop is arrested by the stop the other carbon or conductor will be kept sufficiently away to form the voltaic arc, and so that the stop may be shifted to let the carbons come in contact, substantially as specified.

8. In a voltaic-arc electric lamp, two carbons or conductors, means for impelling them toward each other, means for connecting them so that one cannot be moved without occasioning motion in the other, an adjustable stop against which one of the carbons or conductors bears, and an electro-magnet in the lamp-circuit for actuating said stop, all being so combined and organized that when the carbon or conductor which bears against the stop is arrested by the stop the other carbon or conductor will be kept away sufficiently to form the voltaic arc, and so that the stop is rendered operative and inoperative when the lamp is supplied with an electric current and deprived of it respectively, substantially as specified.

9. In a voltaic-arc electric lamp, two carbons or conductors, means for impelling them toward each other, means capable of adjustment for connecting them in different relations to each other, but so that one cannot be moved without occasioning motion in the other, and a stop against which one of the carbons or conductors bears, all being so combined and organized that when the carbon or conductor which bears against the stop is arrested by the stop the other carbon or conductor will be kept away sufficiently to form the voltaic arc, substantially as specified.

10. In a voltaic-arc electric lamp, two car-

bons, means for impelling them toward each other, gear-wheels connecting them together, so that one cannot be moved without occasioning motion in the other, an adjustable connection between one of the gear-wheels and its shaft, and a stop against which one of the carbons or conductors bears, all being so combined and organized that when the carbon or conductor which bears against the stop is arrested by the stop the other carbon or conductor is kept away sufficiently to form the voltaic arc, substantially as specified.

11. In an electric lamp, the combination, with a base-plate containing carbons or conductors and their appurtenances, of arms or hangers for supporting the same, contact-pieces attached to the arms or hangers and adapted to connect the circuit-wires through the carbons or conductors, a globe-holder, 15 hooks attached to the arms or hangers and engaging with the globe-holder, and means attached to the base-plate for securing it to the globe-holder, substantially as specified.

12. In an electric lamp, the combination, with a base-plate containing carbons or conductors and their appurtenances, of the arms or hangers H' , for supporting the same, the contact-pieces I, for connecting the circuit-wires through the carbons or conductors, the hooks N, and the globe-holder h , substantially as specified.

13. In an electric lamp, the combination, with a base-plate containing carbons or conductors and their appurtenances, of the arms or hangers H' , for supporting the same, the contact-pieces I, for connecting the circuit-wires through the carbons or conductors, the hooks N, the globe-holder h , and the lugs j , and screws k on the base-piece, substantially as specified. 35
